(57) The ornamental design for a spray suppression device for a vehicle, as shown and described.

DESCRIPTION

FIG. 1 is a perspective view, showing my new design of a spray suppression device for a vehicle comprising a series of components, wherein the separations indicate no particular height;

FIG. 2 is a perspective view showing my new design, from another angle, of the spray suppression device for a vehicle comprising a series of components, wherein the separations are again used to indicate no particular height;

FIG. 3 is an end view thereof;

FIG. 4 is a top plan view thereof; and,

FIG. 5 is a bottom plan view thereof.

The broken lines showing additional spray suppression components show the spray suppression device and such components in one condition of use.
